R. C. BEEKMAN.
WASHING MACHINE.
APPLICATION FILED FEB. 9, 1920.

1,382,756.

Patented June 28, 1921.

WITNESS:

L. J. Fischer

INVENTOR:

Ross Clark K. Beekman

UNITED STATES PATENT OFFICE.

ROSS CLARK BEEKMAN, OF KANSAS CITY, KANSAS.

WASHING-MACHINE.

1,382,756.

Specification of Letters Patent. Patented June 28, 1921.

Application filed February 9, 1920. Serial No. 357,205.

To all whom it may concern:

Be it known that I, ROSS CLARK BEEKMAN, a citizen of the United States, residing at Kansas City, in the county of Wyandotte 5 and State of Kansas, have invented certain new and useful Improvements in Washing-Machines, of which the following is a specification.

My invention relates to washing machines and the object of the invention is to provide an apparatus of this character in which the washing is accomplished by pressure, rather than by friction and rubbing, which latter has a tendency to tear the garments.

The machine is simple and durable in construction, there being few parts to get out of order or wear out. Another object is to produce a machine which is easy to operate and 20 quick in completing a washing.

With the above and other objects in view, reference will now be had to the accompanying drawing, in which:

Figure 1 shows a longitudinal section of 25 my machine.

Fig. 2 is a longitudinal elevation of the main roller of the machine.

Fig. 3 is an inverted plan view of a roller bed forming an important part of the invention.

Fig. 4 is an enlarged detail view of the tensioning means employed on my machine.

Fig. 5 is a cross section of the main roller, together with the roller bed.

Fig. 6 is a view of one of the end plates forming part of the roller, also showing the crank by means of which the machine is ordinarily operated.

In carrying out my invention, I employ a 40 tub 2 for holding water or a washing fluid, said tub being supported by any suitable means, as legs or standards 4, having braces 6. The tub 2 is made of any suitable material as metal or wood and is provided with 45 a pair of longitudinal braces 8 running from end to end of said tub and secured thereto in any suitable manner, as for instance, bolts 10 being shown in the present case.

12 designates a pair of rockable arms, 50 which are secured at one end to a pivot 14, their opposite end being free to swing up, along the arcuate dotted line. Said arms 12 are provided at their free ends with notches 16 adapted to engage over studs or pegs 55 cured in the longitudinal braces 8, thus serving to secure the device firmly in position

while in operation. These arms 12 are swung upwardly along the dotted line, and thence backwardly and allowed to rest against the end of the tub 2, when the same 60 is being filled or emptied of clothes or garments being washed.

20 designates a pair of arms extending upwardly at an oblique angle, said arms being secured at their lower ends to the main longitudinal braces 8.

A pair of arms 22 are pivotally mounted at the upper ends of said arms 20, being secured by bolts 24, thus allowing them to move freely up and down to a limited extent.

26 designates a pair of retractile springs secured at one end to the forward ends of the arms 22, and having threads formed on their rear extensions which pass through holes in brackets 30 and have wing nuts 32 threaded thereon, by means of which the tension on said springs may be regulated, and thus in turn, secure the desired adjustment between the main roller and the roller bed.

38 designates a pair of notches in which is mounted a main roller 40, having a crank 42 and a handle 44 by means of which said roller may be rotated or oscillated. Said roller consists of two circular end plates 46 75 having a series of triangular projections 48 between which are fitted a number of slats or bars 50, thus forming a neat and durable roller. Said roller is mounted upon a shaft 52, which latter is journaled in notches 38.

The roller bed consists of a pair of oppositely-disposed head blocks 56 held together by tie rods 58 having nuts 60, and provided with trunnions 61 journaled in notches 63 in bearing blocks 54. 62 designates a plurality 95 of rollers journaled in said head blocks 56, the whole thus forming a roller bed which operates in conjunction with the main roller 40, and between which the articles being washed are allowed to pass.

The operation briefly stated is as follows: When it is desired to do some washing, the tub is filled to the desired depth with water or other suitable washing fluid. The roller bed and the main roller, together with the adjacent parts, are then swung backwardly along the dotted lines, thus allowing the tub to be easily and quickly filled. Said roller bed and the adjacent parts are then swung downwardly to operative position, 110 and the garments are placed, one by one, between the main roller and the roller bed and

the hand crank is then rotated or oscillated back and forth until the garment is thoroughly washed and cleansed. It will thus be seen that washing of the garments is accomplished by pressure alone, and not by friction or rubbing as in the usual manner, thus preserving said garments from wear and tear. Also owing to the spring-like and adjustable construction, any manner of garment may be washed, from the coarsest blanket, to the finest piece of lace. While I have shown my machine adapted to be operated by hand power in the present case, it is to be understood that it may also be operated by an electric motor or other power, by merely removing the hand crank and substituting a pulley or sprocket wheel therefor.

From the foregoing description it will be understood that I have provided a washing machine well adapted for the purpose intended, and while I have shown the preferred construction of my machine, I reserve the right to make such changes, in the propor-

tion, combination and arrangement of parts, as properly fall within the spirit and scope of the appended claim.

Having thus described my invention, what I claim and desire to secure by Letters Patent, is:

In a washing machine, a main roller consisting of two circular end plates, triangular projections on said end plates near the periphery thereof, slats which are substantially rhomboidal in cross section having their ends adapted to fit between the triangular projections on the end plates to form a roller, a shaft upon which said roller is journaled, means for rotating or oscillating said shaft and its roller, and a roller bed coöperating with said main roller, substantially as described.

In testimony whereof I affix my signature, in the presence of two witnesses.

ROSS CLARK BEEKMAN.

Witnesses.

L. J. FISCHER,
FRED C. FISCHER.
